UNITED STATES PATENT OFFICE.

ROBERT F. MONAHAN, OF BUFFALO, NEW YORK.

HANDLE-BAR.

SPECIFICATION forming part of Letters Patent No. 777,385, dated December 13, 1904.

Application filed February 20, 1904. Serial No. 194,484. (No model.)

To all whom it may concern:

Be it known that I, ROBERT F. MONAHAN, a citizen of the United States, and a resident of Buffalo, in the county of Erie and State of New York, have invented a new and Improved Handle-Bar, of which the following is a full, clear, and exact description.

My invention relates to handle-bars, and more particularly those adapted for use upon bicycles and the like, and has for its principal object the provision of a yielding bar in which the resisting tension may be adjusted.

Reference is to be had to the accompanying drawings, forming a part of this specification, in which similar characters of reference indicate corresponding parts in all the figures.

Figure 1 is a central vertical longitudinal section through one embodiment of my invention on the line 1 1 of Fig. 3. Fig. 2 is a central horizontal section therethrough on the line 2 2 of Fig. 3. Figs. 3, 4, 5, and 6 are respectively transverse sections on the lines 3 3, 4 4, 5 5, and 6 6 of Fig. 1; and Fig. 7 is a perspective view of the separated heads and clutch mechanism.

10 designates a supporting-sleeve which may be carried, as usual, upon the handle-bar post, within which is an internal supporting-sleeve 11, separated from the outer sleeve by 15 a spacing-collar 12. As the handle-bar and coöperating elements upon each side of this support are the same, but one will be herein described.

Within the sleeve 11 and just to one side of 20 the center thereof is situated a head 13, secured in place by a pin 14 extending through it and the supporting-sleeves. From this head a stem 15 projects outwardly, and encircling this is a spiral torsion-spring 16, having a bent end 17, serving to retain it against rotation by engagement with a groove 18, extending along one edge and across the inner side of the head 13. The opposite end of this spring surrounds a similar spindle 19, and its 25 bent end enters a groove 20 in a head 21, which is fastened to the handle-bar B just outside the end of the sleeve 11 by a transverse pin 22. The bar is rotatable on said sleeve and is shown as extending under the external sleeve, 30 the spacing-collar being of such thickness as

to admit of this. The spring 16 exerts sufficient longitudinal tension upon the bar to hold it firmly upon the support while permitting it to rotate thereon against its torsional resistance.

Just beyond the head 21 on the opposite side from the end of the supporting-sleeve is a clutch member, here shown as consisting of a sleeve 23, having oppositely-situated end projections or teeth 24 24, which pass through 35 longitudinal grooves or openings 25 25 in the periphery of the head 21. These projections coact with a companion clutch member, this being furnished by recesses in the end of the sleeve 11, leaving between them teeth 26. 40 The relative width of these clutch recesses and projections is such that the latter are allowed some rotary movement in the former. To compel the rotation of the clutch-sleeve 23 with the bar while permitting it to move longitudinally, it is provided with a projection here shown as consisting of a screw 27, threaded into the clutch-sleeve, having its end passing through a longitudinal slot 28 in the bar. 45

The clutch members are preferably held in 50 engagement by a spiral compression-spring 29 interposed between the end of the clutch-sleeve and a head 30, which may be secured in the handle-bar by a transverse pin 31.

The operation of the device is as follows: 55 The clutch members are so engaged that the projections upon one are held against one side of the recesses of the other with some force by the torsion of the spring, the direction being such that the pressure of the arms of the 60 rider causes it to yield, absorbing vibration and relieving him from the jar. When it is desired to adjust the tension or force which opposes this yield, the clutch members are separated by the outward movement of the sleeve 65 23 and the spring tension increased or diminished by twisting the handle-bar upon the supporting-sleeve to an angle at which the projections may secure a new engagement with the recesses.

Having thus described my invention, I claim as new and desire to secure by Letters Patent—

1. A handle-bar comprising a sleeve, a bar rotatable upon the sleeve, a spring within the sleeve secured thereto and to the bar, teeth 70

- upon the end of the sleeve, and a toothed member rotatable with the bar and longitudinally movable therein for coaction with the sleeve-teeth.
5. 2. A handle-bar comprising a sleeve, a bar rotatable upon the sleeve, a spring within the sleeve secured thereto and to the bar, teeth upon the end of the sleeve, a toothed member rotatable with the bar and longitudinally movable therein for coaction with the sleeve-teeth, and a spring normally maintaining the coaction of the teeth.
10. 3. A handle-bar comprising a sleeve, a bar rotatable upon the sleeve, a spring secured to the sleeve, a head fast within the bar, and a clutch member upon the opposite side of the head from the sleeve for coaction with said sleeve.
15. 4. A handle-bar comprising a sleeve, a bar rotatable upon the sleeve, a spring secured to the sleeve, a head fast within the bar and provided with longitudinal openings, and a clutch member having projections extending through

the head - openings and coacting with the sleeve. ²⁵

5. A handle-bar comprising a sleeve, a bar rotatable upon the sleeve, a spring secured to the sleeve, a head fast within the bar, and a clutch member having a side projection extending through the bar and end projections ³⁰ coacting with the sleeve.

6. A handle-bar comprising a sleeve, a bar rotatable upon the sleeve and provided with a longitudinal slot, a spring within the sleeve secured thereto and to the bar, a clutch member coacting with said sleeve, and a screw extending through the bar-opening and threaded into the clutch member. ³⁵

In witness whereof I have signed my name to this specification in the presence of two sub- ⁴⁰ scribing witnesses.

ROBERT F. MONAHAN.
